AUTOMOTIVE STEREO CARTRIDGE HOLDER

Theodore Ritz, Jr., 9939 Deering,
Livonia, Mich. 48150

Filed July 5, 1966, Ser. No. 2,982

Term of patent 14 years

Int. Cl. D3—99; D9—04

U.S. Cl. D87—1

FIG. 1

FIG. 2

FIG. 3

FIG. 4

FIG. 5

FIG. 6

FIG. 1 is a perspective view of an automotive stereo cartridge holder embodying my design;
 FIG. 2 is a side elevational view thereof;
 FIG. 3 is a top plan view thereof;
 FIG. 4 is a front elevational view thereof;
 FIG. 5 is a rear perspective view thereof; and
 FIG. 6 is a fragmentary perspective view thereof.
 The automobile dashboard in broken lines is shown for illustrative purposes.

I claim:

The ornamental design for an automotive stereo cartridge holder, as shown and described.
